PIN LOCK

Filed Sept. 26, 1928

Inventor:

Jerome K. Blakeslee,

By Wilkinson, Shirley, Byron & Knight
Atty.

UNITED STATES PATENT OFFICE

JEROME K. BLAKESLEE, OF CHICAGO, ILLINOIS, ASSIGNOR TO AMERICAN STEEL FOUNDRIES, OF CHICAGO, ILLINOIS, A CORPORATION OF NEW JERSEY

PIN LOCK

Application filed September 26, 1928. Serial No. 308,372.

This invention relates to a pin lock, and more particularly to a lock for preventing a pin from being withdrawn from a brake hanger, brake lever or other attaching element.

It is usual in railroad practice to secure in place removable pins by the use of cotters, which many times are poorly set in place and the legs of which are not properly spread for holding the cotter in locking position. As a result thereof, pins forming connections between parts to be connected are often inadvertently moved out of operative association with said parts, resulting in a disconnection rendering structures inoperative.

One object of the invention is to provide a snap-on type of lock for a headed pin which will securely lock itself to the pin and prevent accidental disconnection of parts connected to the pin.

Another object is to provide a lock for a headed pin in which the various parts thereof are arranged in a cooperative manner to meet all of the requirements for the intended purpose.

These and other objects are accomplished by means of the arrangements disclosed on the accompanying sheet of drawing, in which—

30 Figure 1 is an elevational view of a headed pin having applied thereto one form of lock embodying my invention, the lock being shown in section and applied to the pin;

35 Figure 2 is a front elevation of the lock; Figure 3 is a side elevation of the same lock;

Figure 4 is a view similar to that shown in Figure 1 and disclosing a modified form of lock, said lock being shown in section;

40 Figure 5 is a front elevation of the modified form of lock; and

Figure 6 is a side elevation of the same lock.

The various novel features of the invention will be apparent from the following description and drawing and will be particularly pointed out in the appended claims.

Referring first to Figures 1 and 4 of the drawing, it will be noted that my invention is 50 illustrated in connection with a pin 10 hav-

ing a relatively large head 11 at one end and a collar or a relatively small head 12 at the other end, the latter of which is formed by a circular groove 13 which may be formed in the pin at the time the pin stock is cut. 55 The pin 10 may be mounted in any suitable member 14, such as a brake lever, hanger or other member in which it is to be secured.

The invention relates particularly to the lock itself. In Figures 1, 2 and 3, there is shown a lock embodying one form of my invention. This lock includes a continuous wall having four sides 15, 16, 17 and 18, within the confines of which the head 12 is received when the lock is set in locking position. The side wall 15 of itself may be considered to be U-shaped in that it has an enlarged slot 19 for the reception of the reduced portion 20 of the pin 10. When the lock is set in position, as shown in Figure 70 1, the upper portion of the side wall 15, or the base of the U-shaped wall, engages the inner side of the pin head 12. The opposite side wall 16 has a tongue 21 which engages the outer side of the head 12 so that when the lock is in position, the side wall 15 and the tongue 21 of the wall 16 actually engage or embrace the pin head 12. The tongue 21 in turn is provided with a depending projection 22 having an inturned locking rib 23 which engages the periphery of the head 12 for securely locking the lock member to the pin against accidental displacement. The side walls 17 and 18 act as spacing and supporting walls for the side walls 15 75 and 16. 80

85 In the modification shown in Figures 4, 5 and 6, the four side walls 24, 25, 26 and 27 are provided, side wall 25 having a tongue 28, but instead of said tongue 28 in turn having a depending projection, the side wall 25 itself directly has an offset locking projection of rib 29 which is adapted to engage the periphery of the head 12; otherwise the parts are substantially the same as shown in 90 Figures 1, 2 and 3, and operate in the same manner.

95 There may be various other modifications of the invention as herein particularly shown and described, and it is my intention to 100

cover all such modifications of the invention which do not depart from the spirit and scope thereof as defined in the following claims.

I claim:

- 6. 1. A lock for a headed pin or the like, including laterally spaced walls, portions integral with said walls and in planes other than the planes of said walls, one of said walls provided with an opening for receiving the head of the pin and adapted to be located on one side of said pin head, the other wall being located on the opposite side and having a resilient portion extending toward and contacting said pin for drawing said first-named wall into engagement with the head of said pin thereby tending to hold said lock against rotation, said last named portion having means for securing said lock to said pin.
- 10. 2. A lock for a headed pin, comprising a member having spaced walls, one of said walls having a cut-out portion adapted to fit over the head of said pin, portions adjacent the opening of said cut-out portion integrally connecting said walls together to provide a unitary structure and to offset said walls in spaced relation, the other of said walls having a free end contacting with the
- 15. 30. head of said pin, said last mentioned wall having a locking element adapted to engage with said head for securing said lock to said pin.
- 20. 3. A lock for a headed pin, comprising a member having spaced walls, one of said walls having a cut-out portion adapted to fit over the head of said pin, portions adjacent the opening of said cut-out portion integrally connecting said walls together to provide a unitary structure and to offset said walls in spaced relation, the other of said walls having a free end contacting with the head of said pin for drawing said first-named wall into engagement with the head of said pin thereby tending to hold said lock against rotation, said last mentioned wall having a locking tongue for engagement with said head for securing said lock to said pin.
- 25. 4. A lock for a headed pin, comprising a member having spaced walls, one of said walls having a cut-out portion adapted to fit over the head of said pin, portions adjacent the opening of said cut-out portion integrally connecting said walls together to provide a unitary structure, the other of said walls having a free end contacting with the head of said pin, said last mentioned wall having a tongue struck therefrom and extending toward the opening of said cut-out portion, said tongue having locking means for engagement with said head for securing said lock to said pin.
- 30. 5. A lock for a headed pin, comprising a member having spaced walls, one of said walls being provided with a cut-out portion having an opening along an edge of said

wall, said cut-out portion being adapted to fit over the head of said pin, portions adjacent said opening integrally connecting said walls together to provide a unitary structure and to offset said walls in spaced relation, the other of said walls having a resilient portion contacting with the head of said pin for drawing said first named wall into engagement with the head of said pin thereby tending to hold said lock against rotation.

70. 6. A lock for a headed pin, comprising a member having spaced walls, one of said walls being provided with a cut-out portion having an opening adjacent an edge of said wall for initially receiving said pin so as to position said head between said walls, said cut-out portion being adapted to fit over the head of said pin, portions adjacent said opening integrally connecting said walls together to provide a unitary structure and to offset said walls in spaced relation, the other of said walls having a resilient free end extending from said last named portions adapted to contact the head of said pin for drawing said first named wall into engagement with the head of said pin thereby tending to hold said lock against rotation.

75. Signed at Chicago, Illinois, this 21st day of September, 1928.
